US0D1090418S

(12) **United States Design Patent** (10) **Patent No.:** **US D1,090,418 S**
(45) **Date of Patent:** **** Aug. 26, 2025**

(54) **BATTERY**

(71) Applicant: **ZEBRA TECHNOLOGIES CORPORATION**, Lincolnshire, IL (US)

(72) Inventors: **Sunghun Lim**, Bethpage, NY (US); **Jiwei Huang**, Syosset, NY (US); **Dae Suk Noh**, Vernon Hills, IL (US)

(73) Assignee: **Zebra Technologies Corporation**, Lincolnshire, IL (US)

(**) Term: **15 Years**

(21) Appl. No.: **29/906,046**

(22) Filed: **Oct. 30, 2023**

Related U.S. Application Data

(63) Continuation of application No. 29/809,635, filed on Sep. 29, 2021, now Pat. No. Des. 1,003,235.

(51) **LOC (15) Cl.** **13-02**

(52) **U.S. Cl.**

USPC **D13/103**

Assistant Examiner — Charles Hwang

(57) **CLAIM**

The ornamental design for a battery as shown and described.

DESCRIPTION

FIG. 1 is a first perspective view of a battery;

FIG. 2 is a second perspective view thereof;

FIG. 3 is a back view thereof;

FIG. 4 is a front view thereof;

FIG. 5 is a first side view thereof;

FIG. 6 is a second side view thereof;

FIG. 7 is a top view thereof; and,

FIG. 8 is a bottom view thereof.

The broken lines are directed to environment and are for illustrative purposes only. Broken lines form no part of the design claimed.

1 Claim, 6 Drawing Sheets
